UNITED STATES PATENT OFFICE.

CARL BUSCH THORNE, OF HAWKESBURY, ONTARIO, CANADA.

PROCESS AND APPARATUS FOR PRODUCING WOOD PULP.

Application filed April 5, 1926. Serial No. 99,914.

My invention relates to the cooking of cellulosic material to produce pulp and more particularly to the heating and movement of the liquor used in such cooking.

It is well known in the art that wood in the desired form may be cooked in a digester with different types of liquor, to free the wood from its encrusting materials and liberate the fibre and my process is applicable to the use of any of the usual cooking liquors. Difficulty has been encountered in providing apparatus which will withstand the corrosive effects of various cooking liquors and large quantities of steam are required for maintaining the required cooking temperatures as well as for the circulation of the liquor and pulp.

It is an object of my invention to provide a novel process and means for moving or circulating the cooking liquor.

A further object of my invention is to provide a process and means for supplying the digester, filled with wood, with a liquor at substantially the required cooking temperature and pressure.

A still further object of my invention is to utilize the heat contained in the waste gases and liquor, incident to the operation of the process, for preheating the cooking liquor.

Further objects of my invention are to shorten the time required for cooking the wood; to reduce the amount of liquor required; to obtain a thorough circulation of the cooking liquor; to produce a uniform quality of pulp for the manufacture of paper, silk and other articles of commerce, to obtain a high yield from the digester and generally to provide an improved, easily controlled process for economically cooking wood, all of which will appear from the detailed description now to be given.

While, as previously stated, my process and apparatus may be used with any cooking liquor, I shall describe it with particular reference to the so-called sulphite process. In this process it is particularly desirable to retain the SO_2 gas in the liquor. When the liquor is heated there is a tendency for the SO_2 to be liberated and to avoid this I maintain the heated liquor, under a pressure. This I accomplish by the use of a gas, which may be circulated as desired through the apparatus, as will hereinafter appear. Any desired gas may be used, which will not form undesirable reactions with the liquor. In

this particular operation of the process SO_2 gas is very effective. I have also used nitrogen, but any suitable gas may be employed.

The accompanying drawing illustrates 60 diagrammatically and by way of example one form of the apparatus of my invention as used for the operation of the process.

The tank 1 is an ordinary storage tank for the supply of cooking liquor and it is connected through the pump 2 to a series of heaters 3^a, 3^b, 3^c, a valve 4 being provided to regulate the discharge from the tank. The heaters are provided with heating coils 5. The pipe 6 is provided with a check valve 7 and leads to a hot liquor tank 8, which is connected to a circulating or pulsating tank 9 by means of pipes 10 and 11 having valves 12 and 13. This tank 9 is connected by means of an extension of pipe 11, having valve 14, 75 through a heater 15 to the cooking liquor line 16 which as indicated leads to a series of digesters 17^a and 17^b. Only two such digesters are shown but any desired number may be used. The pipe 18^a, having a valve 19^a, leads 80 from the liquor line 16 to the top of the digester 17^a and the pipe 18^b having the valve 19^b leads to the top of the digester 17^b, while the liquor line 16 is connected to the bottom of the digesters by means of pipes 20^a and 85 20^b having valves 21^a and 21^b respectively.

The tank 22 is for gas storage and is connected through a compressor 23 to a compressed gas supply tank 24 by means of a pipe 25 having a valve 26. A compressed 90 gas supply line 27 leads from tank 24 and is connected by means of pipes 28^a, 28^b, 28^c and 28^d, having valves 29^a, 29^b, 29^c and 29^d respectively, to the hot liquor tank 8, the pulsating or circulating tank 9 and the digesters 95 17^a and 17^b respectively. A pipe 30 having a safety valve 31 leads from the compressed gas tank 24 to the tank 22. A gas relief line 32, having a safety valve 33, is connected to the hot liquor tank 8, the pulsating tank 100 9 and the digesters 17^a and 17^b respectively by means of the pipes 34^a, 34^b, 34^c and 34^d having valves 35^a, 35^b, 35^c and 35^d respectively. This gas relief line 32 conveys the relief gases to the heaters and or to a gas recovery device. A pipe 36 having a stop valve 105 37 and a safety valve 38 connects the tank 8 with the gas supply tank 22.

The digesters are of the usual construction and when required are lined with a material 110 resistant to the action of the cooking liquor used. The liquor tank 8 and the circulating

or pulsating tank 9 are of similar construction and are likewise resistant to the action of the liquor employed and capable of withstanding the pressures incident to the working of the process.

The heaters 3^a, 3^b and 3^c are made of or lined with a material resistant to the action of the cooking liquor. Any desired number of heaters may be employed and they may 10 be heated in any desired way, but in accordance with my invention, I prefer to utilize the heat from the waste products of the process for this purpose. Thus the hot waste liquors from the blow pit, well known in the art and 15 consequently not shown in the drawing, may be passed through the coil 5 in the heater 3^a, while the relief products from the digesters may be passed through the coil 5 in heater 3^b and live steam, a hot gas or fluid or even a 20 direct flame may be used for heating the heater 3^c, to finally bring the temperature of the liquor passing therethrough to the required temperature. If desired the liquor may be circulated through the coils 5 and the 25 heating medium about them. In any case, when spent liquors are used as the heating medium, I maintain the pressure of the heating medium higher than that of the liquor, passing through the heaters, so that should 30 leaks occur the fresh liquor will not escape into the heating medium.

Moreover, an additional heating element, not shown, may be placed in tank 8 to further assist in raising the temperature of the 35 liquor. The heater 15 may be of any desired type and may have a heating coil 15^a therein.

The pump 2 is designed to be adapted to fill the hot liquor tank 8 against a pressure of approximately 100 lbs. as in accordance 40 with my invention, a constant pressure is maintained on the liquor in this tank. The safety valves are designed to maintain a predetermined desired pressure in the respective parts of the apparatus.

45 The operation of my process and apparatus is as follows:

By means of the compressor 23 gas from the supply tank 22 is forced into the compressed gas supply tank 24, from which it 50 is passed through pipes 27 and 28^a into the hot liquor tank 8, until a pressure of approximately 70 lbs. is produced therein, when valve 29^a is closed. The valve 37 being open the safety valve 38 maintains a constant pressure 55 sure in tank 8.

Liquor is pumped from the liquor supply tank 1 through the heaters 3^a, 3^b and 3^c where it is heated to a temperature of 100°-130° C. more or less, depending on the pressures 60 employed, into the tank 8 under pressure, while the gas is relieved through pipe 36 and safety valve 38 into the gas supply tank 22. When the tank 8 is substantially filled the valve 4 is closed and the pump 2 stopped. 65 The digester 17^a having been filled with

chips in the usual manner, valve 29^c is opened and gas is allowed to pass into the digester until a pressure of substantially 70-100 lbs. is reached, depending upon the cooking pressure employed, when valve 29^c is closed. 70 Valves 12, 14, 21^a, 29^a and 35^c are opened, and valve 35^a being closed hot liquor is forced into the digester from the bottom, while the gas from the digester is relieved through pipe 34^c, the relief line 32 and safety valve 75 33. This movement of the liquor is caused by the pressure of the gas on the liquor in tank 8. If it is desired to fill the digester from the top, it will be apparent that valve 19^a would be opened instead of valve 21^a or the liquor 80 may be run into the digester from both top and bottom by opening both these valves. When the digester is filled with liquor the valves 21^a and 19^a, 14, 12 and 29^a are 85 closed and if it is necessary to further raise the temperature steam may be admitted to the digester in the usual manner.

It will be apparent that, inasmuch as the liquor is introduced into the digester at a temperature of about 100-130° C. and under 90 a pressure of about 70-100 lbs. the cooking process will begin at once, thus a substantial reduction in the time required for completing the cook and in the steam consumption is effected. In order, however, to effect a further saving in this regard and to produce a 95 more uniformly cooked product, I provide for circulation of the liquor in the following manner.

Valve 29^b is opened to allow gas to flow 100 from the tank 24 to the circulating or pulsating tank 9 until the pressure therein becomes substantially equal to that in the digester, when valve 29^b is closed. Valves 29^c, 21^a, 14 and 13 are opened and gas from the compression tank 24 flows into the digester forcing the liquor out into the tank 9, while at the same time valve 35^b is opened to permit the relief of the gas from tank 9. When the desired amount of liquor has been withdrawn 110 from the digester valves 35^b, 29^c and 21^a are closed and valves 19^a, 35^c and 29^b are opened and the liquor from the tank 9 is forced into the top of the digester. If desired the liquor may be forced directly back into the bottom 115 of the digester, thus causing what I term, a pulsation in the digester, instead of the straight circulation of the liquor. This circulating or pulsating operation is repeated as often as desired in connection with the 120 particular material being treated. Obviously while I have shown the liquor as being removed from the bottom of the digester, it may be withdrawn at any desired point.

The cooking operation may thus be completed or I may proceed as hereinafter described.

Thus far I have not described the operation of the digester 17^b or other members of the series of digesters which I may employ, 130

but it will be apparent that they may be employed in the same manner as digester 17^a just described, each digester operating as an independent unit.

- 5 In the treatment of some classes of wood it may be preferable to operate the digesters successively or in conjunction one with another and my invention comprehends such method of operation. Thus after the charge 10 of chips in digester 17^a has been cooked for a period of time, as above described, I may transfer the liquor from this digester to digester 17^b, which has previously been filled with chips and has a gas pressure of about 70 15 lbs. therein, by opening valves 29^c, 21^a, 21^b and 35^d. When the liquor is transferred from digester 17^a to digester 17^b, these valves are closed and if necessary steam is admitted to digester 17^b and the cook progresses therein. 20 A further charge of fresh liquor from tank 8, of used liquor from one of the digesters of the series, or even of liquor from a source, not shown, is then forced into digester 17^a to complete the cooking of the charge. I 25 also contemplate the treatment of the chips in the digester with more than the two treating liquors specifically mentioned and such liquors will be transferred as required by means of the gas under pressure as previously 30 described. The completely cooked charge is finally transferred to the blow pit in the usual manner.

While I may admit steam directly to the cooking liquor to raise its temperature, it 35 will be understood that I prefer to employ indirect heating to avoid the dilution of the liquor.

I have not shown in the drawings means for maintaining a higher pressure in the heating medium flowing through the heaters, than that of the liquor being heated, as those skilled in the art may readily provide such means. For example, a pump may be employed to raise the pressure of the waste liquor, coming from the digester to the heater coils, to the required point and pressure valves to maintain such pressure in the coils at all times. Should the pump through accident or other cause be shut down such valves would 40 be designed to maintain the predetermined pressure in the coils and thus prevent the loss of liquor, as previously described.

It will be understood that the term wood used in the specification and claims includes 45 any cellulosic material from which pulp may be made.

It will thus be apparent that in accordance with my process a hot cooking liquor is applied directly to the chips under a sustained 50 pressure and that such liquor is caused to circulate or pulsate in the digester, without the use of a pump or other moving mechanical parts coming into contact with the hot liquor. The heat contained in the waste gases 55 and liquor ordinarily lost, is utilized to raise

the temperature of the cooking liquor, thus reducing the amount of fuel consumed in the cooking of the wood. The additional advantages of my process will be apparent to those skilled in the art.

Having now particularly described my invention, what I claim is:—

1. A process of preparing wood pulp which comprises injecting a preheated liquor into wood chips in a digester against a substantially constant pressure derived from an external gas and causing a circulation of said liquor in the digester, pressure for said circulation being derived from said external gas.

2. A process of preparing wood pulp which comprises forcing a preheated liquor into a digester containing wood chips under pressure, by means of an external body of gas under pressure, so that the digester is charged at substantially cooking temperature and pressure, and cooking the chips therein.

3. A process of cooking wood which consists in preheating a cooking liquor by utilizing heat of waste products of the process, admitting said preheated liquor to a charge of wood chips under a pressure in a digester, said pressure being derived from an external gas, cooking the chips with said liquor and periodically causing the liquor to circulate or pulsate in the digester, pressure for said circulation or pulsation being derived from said external gas.

4. A process of cooking wood which comprises treating wood chips in a digester with a preheated liquor and at a cooking temperature, withdrawing liquor from the bottom of the digester to a circulating or pulsating tank and returning said liquor to the bottom of the digester, the hot liquor being under pressure throughout the operation of the process and the movement of the liquor being effected by a body of gas under pressure.

5. In a process of cooking wood, heating the cooking liquor, charging it into a digester containing wood chips, circulating or pulsating it in the digester and keeping said liquor under a predetermined substantially constant pressure throughout the process.

6. In a process of cooking wood chips with liquor, in a digester, the step which consists in moving the liquor from and to the digester with an external body of gas under pressure.

7. In a process of cooking wood chips with a preheated liquor in a digester, the step which consists in maintaining said liquor under a predetermined substantially constant pressure throughout the operation of the process, said pressure being derived from an external body of gas.

8. A process for cooking wood chips which comprises treating the chips in a substantially gas-tight digester with a series of preheated liquors, and successively transferring said liquors to or from another gas-tight container by admitting gas under pressure into

the container or the digester from which the liquors are to be transferred.

9. A process for cooking wood chips which comprises treating the chips with hot liquor in a digester, admitting gas under pressure to said digester to transfer said liquor to another digester and completing the cook with a second charge of liquor.

10. An apparatus for cooking wood chips comprising a digester, a liquor tank, an external source of independent gas to supply gas under pressure to circulate liquor from and to said tank to and from said digester and means for the release of said gas from the digester and tank as each is being charged with liquor.

11. An apparatus for cooking wood chips comprising a digester, a liquor tank, a liquor circulating or pulsating tank, and an external source of independent gas to supply gas under pressure to maintain liquor in said apparatus under a predetermined pressure and to circulate said liquor in the apparatus.

12. An apparatus for cooking wood chips comprising a digester, a liquor circulating or pulsating tank with connections to the upper and lower portions of said digester, a compressed external gas supply receptacle having connections with said digester and tank adapted to admit compressed gas thereto for the purpose of circulating liquor therein and means adapted to permit the relief of gas from said digester and said tank at a predetermined pressure.

13. An apparatus for cooking wood chips comprising in combination heaters adapted to preheat liquor, a hot liquor tank, a digester, a liquor circulating tank, valve controlled connections between the top and bottom of said digester and said tanks, connections between said tanks, the digester and a compressed gas supply receptacle and means to control the flow of compressed gas through said last named connections, to permit the flow of liquor between said tanks and said digester under a predetermined pressure.

14. An apparatus as defined in claim 11 having an auxiliary liquor heater located between said liquor circulating tank and said digester.

15. An apparatus for cooking wood chips having in combination with a digester and liquor supply and circulating tanks, a compressed gas receptacle and connections adapted to permit the regulated flow of compressed gas to cause the circulation of liquor under a predetermined pressure.

16. An apparatus for cooking wood chips comprising, a series of digesters in combination with liquor heaters, a liquor tank, a liquor circulating or pulsating tank and means adapted to circulate a gas under pressure to effect the transfer of liquor in said apparatus in a controlled manner and to maintain a predetermined pressure in said apparatus.

In testimony whereof I affix my signature.
CARL BUSCH THORNE.
